OIL BURNER

William C. Mason, Albany, N. Y.

Application November 3, 1933, Serial No. 696,562

12 Claims. (Cl. 158—28)

My invention relates to oil burners and particularly to those of the general type described in my copending application Serial No. 577,314, filed November 25, 1931, in which the oil is aspirated and atomized by means of steam and introduced therewith into the combustion chamber. It also relates to novel means for generating the steam and novel means for controlling the operation of the burner.

One of the objects of my invention is to provide, in connection with an oil burner, a simple and inexpensive device for electrically generating steam for the purpose of aspirating and injecting the oil into the combustion chamber in the form of a very fine vapor. Another object is to provide a simple and novel means for controlling the generation of steam. Another object is the provision of a novel means for initially starting the oil burner and for re-igniting it in the event it is, for any reason, extinguished. Another object is to provide a device of the character described in which all danger of explosion, due to the accumulation in the combustion chamber of explosive gases, or to excessive steam pressure, is eliminated. Another object is to provide a small compact unit in which is embodied substantially all of the controls necessary to operate the device safely and efficiently. A still further object is to provide control means which will not only be positive in operation but which will, when the necessity for functioning arises, act quickly.

With these objects in view my invention includes the novel elements and the combinations and arrangements thereof described below and illustrated in the accompanying drawings in which—

Fig. 1 is a plan view of my invention with certain parts removed;

Fig. 2 is a fragmentary vertical section through a fire pot or combustion chamber for a water heater showing details of one of the controls;

Fig. 3 is a fragmentary plan view of a control detail;

Fig. 4 is a fragmentary vertical section, partially in elevation, of a steam generator showing a portion of the control means;

Fig. 5 is a perspective view of a control switch;

Fig. 6 is a plan view, partially in section, of a modified type of control switch;

Fig. 7 is a plan view of the control panel showing some slight modifications in the arrangement thereof shown in Fig. 1;

Fig. 8 is a fragmentary enlarged section in the plane 8—8 of Fig. 4;

Fig. 9 is an enlarged longitudinal vertical section through a nozzle element;

Fig. 10 is a greatly enlarged, fragmentary sectional view of the discharge end of the nozzle;

Fig. 10a is an elevation view of the discharge end of the nozzle;

Fig. 11 is a section of Fig. 9 in the plane 11—11;

Fig. 12 is an enlarged fragmentary rear view of the nozzle and a mounting therefor;

Fig. 13 is a sectional plan view of a control detail;

Fig. 14 is a fragmentary vertical section of an oil filter;

Fig. 15 is a section of Fig. 13 in the plane 15—15;

Fig. 16 is a perspective view of a detail;

Fig. 17 is a perspective view of a water valve detail;

Fig. 18 is a fragmentary vertical section through the water valve;

Fig. 19 is a plan view of the water valve spring;

Fig. 20 is an elevation view of the water valve spring;

Fig. 21 is a fragmentary schematic perspective view of my device showing the connections of the oil and water pipes thereto; and

Fig. 22 is a wiring diagram.

Referring to the drawings, 1 represents, generally, a steam generator comprising a lower base element 2 and an upper base element 3 between which is secured a cylindrical enclosing element 4, the upper and lower bases being secured together by means of bolts 5 (see Figs. 1, 4 and 21).

Integral with the lower base 2 is a cylindrical depending portion 6 through which the water is introduced into the generator. The portion 6 is provided with a central passage 7 extending therethrough. This passage varies in size and the smallest portion thereof is at about the center of the portion 6.

Above the center, the passage is slightly enlarged, as shown at 8, to receive a needle valve 9 which is seated at the upper end of the smallest portion of the passage 7.

Above the slightly enlarged portion 8, the depending portion of the base is counter-bored, as shown at 10, to receive a helical spring 11 which is compressed between the head 12 of the needle valve and the bottom 13 of the counter-bore.

Immediately below the most restricted portion of the passage 7 is an enlarged portion 14 which is interiorly threaded to receive a needle valve 15.

The valve 15 comprises a screw flattened on two sides as shown at 16 to provide a passageway for water and the upper end of the screw is pointed so that it may be seated in a comple-

55 30 35 40 45 50 55 60 65 70 75 80 85 90 95

mentary portion provided in the element 6. Below the portion 14 the depending part 6 is counter-bored as shown at 17 and the lower end is closed by means of a cap 18. The lower portion 5 is also exteriorly reduced in size, as shown at 19, and is provided with a circumferential groove 20 which communicates with the counter-bored portion 17 by means of an opening 21. Surrounding the grooved portion 20, is a collar 22 provided 10 with a nipple 23 exteriorly threaded at 24 to adapt it to be connected to a water supply pipe, and interiorly threaded, as shown at 25, to receive a hollow plug 26 forming part of the ball check valve 27. The ball 27 ordinarily seals the 15 water passage 28 in the plug 26 by compression of a spring 29. The collar 22 is secured in position about the reduced portion of the depending element 6 by means of the cap 18 and suitable gaskets 30 and 31 are provided at the top and 20 bottom in order to insure a water tight connection.

A ball 32 rests on top of the needle valve 9, and the needle valve 9 is normally held in closed position by means of a slide valve 33 which is 25 adapted to be reciprocated across the opening 34 in the lower base.

The interior portion of the lower base 2 is threaded, as shown at 35, to receive the cup or disc 36 which is provided with a peripheral flange 30-37 within which is seated a carbon electrode 38. A star spring 39, shown in detail in Figs. 19 and 20, is interposed between the disc 36 and the slide valve 33 and serves to retain the slide valve 33 in yielding contact with the base 2.

35 The lower base of the slide valve is provided with a spherical or cylindrical depression 40 of somewhat larger diameter than the ball 32 and into which the ball 32 is adapted to be received when the valve 33 is slid to the left as shown in 40 Fig. 18. When the ball 32 is in the depression 40 the needle valve 9 is raised from its seat by spring 11 so that water can flow upwardly through the passages 8 and 10 and under the slide valve into the generator. The slide valve 45 may comprise a rectangular metal block having a cross-shaped recess 77 at one end adapted to receive the operating or connecting rod 76 with a nut 79 thereon. To provide for adjustment of the slide valve, it is provided, near the end opposite the connecting rod with a vertically extending threaded hole adapted to receive the adjusting screw 41. This screw extends through the slide valve and it may be so adjusted that its lower end rides on the upper portion of the base 55 2, as best shown in Fig. 18, thus slightly raising or tilting the block as here illustrated.

The disc 36 is perforated, as shown at 42, and the carbon electrode 38 is provided with vertically extending passages 43 through which the water 60 flows upwardly into the steam generator.

The carbon electrode 38 is preferably cup-shaped, as shown in Fig. 4, and is provided with a plurality of circumferential openings or passages 44 for the free flow of water therethrough. 65 The electrode 38 is provided with a central stud or stem 45 of porcelain which is received within an opening in the upper carbon electrode 46 and which serves not only to maintain the electrode 46 concentric with the electrode 38 but laterally 70 and vertically spaced therefrom, as shown at 47 and 48, respectively. The electrode 38 is grounded. Threaded into the electrode 46 is a metal conductor 49, the upper portion of which is enclosed in an insulating collar 50 extending outwardly through the upper base 3. A suitable

packing nut 51 is provided around the insulating collar 50 where it passes through the upper base 3 and nuts 52 are threaded on the top of the conductor 49 to facilitate the connection of an electrical conductor thereto. 5

In the embodiment of my invention illustrated in the drawings, the burner jet or nozzle, represented generally by the numeral 53, is located on the upper base 3. The details of the nozzle are shown in Figs. 8, 9, 10, 11 and 12. A boss 54, 10 shown in section in Fig. 8, is cast on the top of the upper base 3. The passageway 55 (see Fig. 8) extends upwardly through this boss to the nozzle 56. The nozzle proper may be very small and except for the tip is preferably square 15 or rectangular in cross section. It may be from $\frac{1}{8}$ " to $\frac{1}{16}$ " square and is conveniently made as follows:

A square rod is cut to the desired length to form the nozzle blank and the discharge end is 20 turned to the shape shown in Fig. 10, the extreme end portion being cylindrical. The blank is then drilled axially from the rear end almost through to provide a steam passage 57 of comparatively large size. A comparatively small passage 57' is 25 then drilled from the discharge end in axial alignment with and to meet passage 57. A second passage 59, for oil, is also drilled axially of the blank and in spaced relation to passage 57. This passage terminates short of the rear end of the 30 blank. Transverse passages 60 and 60' are then drilled to meet passages 57 and 59, respectively. The passage 60 is preferably counter-bored for a short distance and a small section of screen 61 35 pressed therein to serve as a filter for the steam. The rear end of passage 57 is sealed, preferably with a screw plug 62 of low melting point metal which is threaded therein. In case of fire about the exterior of the nozzle this plug will fuse and the fuel supply to the nozzle will be cut off because the steam used to aspirate it will escape through the opening thus provided. A cap 63 40 having a central opening 63' therein aligned with passage 57' and having an annular recess 64 about the opening 63' on the inner side thereof is then pressed over the cylindrical discharge end of the nozzle blank. The inner face of the cap is slightly spaced from the end of the nozzle blank as shown at 65. The recess 64 forms an oil chamber entirely surrounding the orifice of passage 57' 50 through which the aspirating steam is forced, and the oil is drawn into the space 65 from all directions and projected into the combustion chamber with the steam. A rectangular V-shaped notch may be provided in the top of the boss 54 55 to receive the nozzle, as shown in Fig. 8, the steam passage 55 opening into one side of this notch to register with passage 60 in the nozzle, and an oil passage 69 in boss 54 opening into the other side of the notch to register with passage 60' in the nozzle. Gaskets 70 and 78' may be interposed between the notch and nozzle and the nozzle securely held in the notch against the gaskets by means of the clamp 71 and screw 72.

Oil is aspirated into passage 69 through pipe 73 60 and air may also be admitted to passage 69 through pipe 74, as will be later explained, to cut off the supply of oil to the nozzle. 65

In Fig. 12 I have shown a modified form of nozzle mounting in which the nozzle 56 is secured 70 in a square opening in the boss by means of a set screw 72' which in turn may be locked by pin 721, thus making it impossible to remove the nozzle without breaking the expanded end of the pin 721 which forms a seal S. 75

Referring now to Fig. 4, the lower base 2 is provided with a hollow nipple 75 through which passes the connecting rod 76 for the slide valve 33. This connecting rod is shown in detail in Figs. 16 and 18. The end of the slide valve opposite the adjusting screw 44 is provided with a cross-like recess or opening 77 (see Fig. 17). The connecting rod 76 is flattened and threaded at one end as shown at 78 and a nut 79 is threaded thereon. The nut 79 fits in the transverse portion of the slot 77 and the flattened portion of the rod 76 fits in the longitudinal portion of the slot 77. The flattened portion of the rod prevents its turning after it is inserted with the nut thereon in the valve and the purpose of the threaded connection with the nut is to provide relative longitudinal adjustment of the rod and slide valve.

The nipple 75 on the base 2 is exteriorly threaded to receive the flange 80 forming the head of a cylinder in which is enclosed a siphon bellows; the other head of the cylinder is shown at 81. The cylinder itself which may comprise a brass tube 82 is secured between the heads 80 and 81 by means of the cap screws 83.

The interior of the head 81 is provided with a flange 84 which is received within and secured to one end of the bellows 85. The other end of the bellows is sealed by means of the element 86 provided with a peripheral flange 87 and a reentrant center portion 88 which extends around and is laterally spaced from the end of the connecting rod 76. A head 89 is provided on the end of the connecting rod and a helical spring 90 is compressed between a washer 91 beneath the head 89 and the end of the nipple 75. A collar 92 is threaded into the head 81 and, adjustably compressed between the collar 92 and the element 86, is a helical spring 93 which tends to maintain the bellows normally expanded. Passing through the central portion of the collar 92 and threaded into the bottom of the reentrant portion of the element 86, as shown at 94, is a rod 95 the threaded end of which contacts with the head 89 on the connecting rod 76. A removable plug 94' is provided in the upper portion of the head 81 for purging the interior of the expansion chamber of air, and a second plug 95' is provided in the lower portion of head 80 for draining the chamber.

Fig. 7 is a plan view showing the burner controls which lie to the left of the steam generator and expansion chamber, shown in sectional elevation in Fig. 4, and which are operatively connected therewith by the movable rod 95. The general assembly is shown in plan to a smaller scale in Fig. 1 and a portion of the controls is shown in section in Fig. 13. All of the controls shown in Fig. 7 are conveniently mounted on a molded base B of bakelite or other insulating material in which some of the electrical conductors may conveniently be molded.

Referring particularly to Figs. 1, 7 and 13, the rod 95 is provided at its outer extremity with a collar 96 threaded thereon and which is secured in place by a lock nut 97. The part 98 is preferably a brass casting secured to the base B and having, in cross section, the form shown in Fig. 13. Supported between the abutments 99 and 100 and retained in a notch 101 in abutment 99 and in the cup-shaped end of a set screw 102 is a flat spring 103 extending in front of the end 104 of rod 95. The screw 102 is adjusted so to compress the spring longitudinally that it assumes a slightly bowed shape, as shown at 103, but will,

when sufficient pressure is exerted against it by rod 95, quickly snap to the position 103' shown in Fig. 13. In alignment with the rod 95 is a second rod 105 adapted to slide through a boss 106 on the casting 98. The boss is counter-bored as shown at 107 and a helical spring 108 is compressed between the bottom of the counter-bore and an enlarged portion 109 of the rod 105. Between the enlarged portion 109 and the end 104 of rod 95, the rod 105 is reduced in cross section for a short distance, as shown at 110, and this reduced portion passes loosely through an opening in the spring 103, the length of the reduced portion of the rod 105 being such as to allow some longitudinal movement of the rod without affecting the spring. The spring 103, near the end opposite that through which passes the rod 105, is provided with a soft rubber cup 111 having a head or button 112 which is merely snapped through an opening in the spring 103 to secure the cup thereto. When the spring is in the position 103' (see Figs. 13 and 15) the rubber cup seals an opening 113 in the casting 98 which communicates through passage 114 with a pipe 14 which in turn communicates with the oil passage 69 in the boss 54 on top of the steam generator. When the spring 103 is in the position shown in the dotted lines in Fig. 13 and the solid lines in Fig. 7, air may pass through the pipe 14 into the oil chamber 69, but when the spring is in the position shown by the solid lines in Figs. 13 and 15 the rubber cup 111 effectually seals the opening 113 so that no air can pass through the pipe 14 into the oil chamber.

Pivotedly supported at 116 is a lever of insulating material 117, one end 118 of which, contacts, or may contact under certain conditions, with an adjusting nut 119 on the end of rod 105. The other end 120 of the lever 117 contacts through a yielding helical spring 121 with an adjusting nut 122 on rod 123. The rod 123 passes through a gland nut 124 and is connected to a circular flexible diaphragm 125 secured in a recess in the casting 98 by the element 126 threaded therein, a gasket 127 being provided to maintain a tight joint. The space 128 to the right of the diaphragm 125 is sealed except that it communicates with the water supply main through an opening 129 and a pipe 130 (see Fig. 21). A helical spring 131 is compressed between the gland nut and the enlarged inner end of rod 123 secured to the diaphragm 125, and the pressure on the left side of the diaphragm may be adjusted by means of the nut 124.

To the left of the lever, 117 as viewed in Figs. 7 and 13, is a flat spring 132, preferably identical with spring 103, and supported at one end in a notch 133 in a frame 133' of insulating material, and at the other end in the cup-shaped point of a screw 134 threaded into the frame. The screw 134 is so adjusted to effect a longitudinal compression of spring 132 that the spring is supported in a slightly bowed or stressed condition. In alignment with the rod 123 is a plunger 135 which is adapted to move back and forth in a recess in the frame 133', and a helical spring 136 is compressed between the head of the plunger 135 and the bottom of the recess in the frame in which it moves so that the plunger is normally pushed to the right by the compression of the spring which is strong enough, in the absence of any pressure on the rod 123, to force and hold the spring 132 in the position shown in the solid lines. The plunger 135 is provided with a reduced portion 137 which passes loosely through

the spring 132 and which terminates in the enlarged head 138 adapted to contact with the end 120 of the lever 117. Secured to the spring 132 is a second spring 139 carrying the metal contact 140. A second metal contact 141, adapted to coat with the contact 140 when the spring 132 is sprung to the position 132', is secured to the binding post 142. A flexible electric conductor 143 may extend from the spring 139 to a second binding post 144, as shown in Figs. 1 and 13, but I prefer the arrangement shown in Fig. 7 whereby a flexible conductor 143' is merely carried to a binding post 144' molded into the base B and thence, through a molded-in conductor X to the main binding post P.

Referring to Fig. 21, 145 is a fuel oil tank which communicates with a float valve 146 through pipe 147. From the chamber of the float valve which maintains the oil at a constant level and preferably about three inches below the nozzle of the burner, the oil flows through pipe 148 into the filtering device 149, the details of which are shown in Fig. 14. The filtering device comprises a hollow cylindrical element 150 which is closed at the bottom by means of the plug 151, a gasket 152 being interposed between the plug and the cylindrical element 150 to insure a tight connection. Oil flows in through the pipe 148 and downwardly through the passage 153 into the element 150. Interposed between the passage 153 and the plug 151 is a filtering screen 154 which is preferably frusto-conical as shown. The oil passes through the screen and then upwardly through the passage 155 to an adjustable needle valve 156 and thence to a static level in pipe 73, somewhat below the nozzle of the burner, and from which it is aspirated to the burner by steam as will be later explained.

To ignite the fuel a spark plug having terminals 157 and 158 is disposed in front of the nozzle. The electrical circuit which includes the spark plug is automatically closed and broken by mechanism which will hereinafter be described but, in order that the same may be more readily understood it seems desirable first to describe the manner in which the steam is generated and the fuel aspirated to the nozzle.

It is to be understood that the water in the water supply pipe is maintained at a pressure substantially in excess of the maximum pressure which will be developed in the steam generator. Assuming that there is water under pressure in the pipe 130 (see Fig. 21), it is quite evident that this pressure will be exerted on the right hand side of the diaphragm 125, as viewed in Fig. 13. The diaphragm will be pushed or distorted to the left, thus moving the rod 123 to the left and so compressing the spring 132 that it will be forced into the position 132'. This will bring the contacts 140 and 141 together. So long as there is adequate water pressure in the water supply line the contacts 140 and 141 will be held together thereby, but, when the water pressure fails, the compression spring 136 will force the plunger 135 to the right, as viewed in Fig. 13, and break the circuit by forcing the spring carrying contact 140 from the position 132' to the position 132. As will be later explained, this contact may also be broken when the steam pressure exceeds a certain predetermined amount.

The switch 159 (see Figs. 1, 7 and 22) is normally closed. This switch is closed manually but is designed, as will be later explained, to open automatically under certain conditions. Switch 181 is a manually operated main switch, and

switch 182 is a thermostatic switch for automatically opening the circuit when the water or building being heated has attained the desired temperature.

By reference to Fig. 22 it will be apparent that when the contacts 140 and 141 are brought together and the switches 159, 181 and 182 are closed a circuit will be established from the power lines 160 and 161 through the carbon electrodes 38 and 46 in the steam generator, the current passing from one electrode to the other through the water in the generator. This passage of current between the electrodes will rapidly heat the water in the generator and steam pressure will be built up therein.

At the start of operations it is to be understood that water has been admitted to the steam generator and stands therein at about the level of the top of the electrode 46. The water level of the generator is indicated by the water level in the glass 162. To admit water to the generator in the first instance it is necessary manually to push or pull the rod 95 to the left, as viewed in Fig. 4, until the slide valve 33 has moved a sufficient distance to release the needle valve 9 from its seat. Water will then flow into the steam generator and when it reaches the proper level the rod 95 is released and the slide valve automatically shuts off the inflow of water. In order that the expansion chamber may be purged of air, the plug 94' at the top of the expansion chamber is unscrewed and the steam generator energized to create pressure sufficient to force water into the expansion chamber and expel the air which would otherwise be entrapped in the top of the expansion chamber. When the water level has reached the desired height, the plug 94' is, of course, replaced.

As the steam pressure builds up in the generator, the water level in the generator is lowered because the steam pressure will force the water into the expansion chamber and compress the bellows 85. As the bellows 85 is compressed, the rod 95 which is associated therewith is moved to the left, and the rod 76 which actuates the slide valve 33 follows the rod 95 as the helical spring 90 expands.

Referring now to Figs. 1 and 7, the end 104 of rod 95 will contact the end of the plunger 108 and tend to force the spring 103 to the position 103' shown in the dotted lines in Fig. 1. The parts are so adjusted that the spring 103 will not snap into the position 103' until the steam pressure has reached a desired maximum of about nine or ten pounds. As the steam pressure builds up in the generator, the steam, of course, issues from the nozzle 53 but the opening in the nozzle is so small that the discharge of steam therethrough does not prevent the building up of the desired pressure.

Steam issuing from the nozzle 53 would ordinarily tend to aspirate oil from its static level in the pipe 73 but due to the fact that the pipe 74 communicates with the atmosphere (see Fig. 15) no oil is drawn up to the nozzle until the spring 103 snaps into the position 103', thus causing the rubber cup 111 to close the opening 113 through which the pipe 74 communicates with the atmosphere. When the spring 103 snaps into the position 103', the rubber cup seals the opening 113 and oil is immediately aspirated and projected from the nozzle with the steam. Before the fuel is projected from the nozzle, it is extremely desirable that the fuel igniting means be put in operation in order to avoid any accumulation of

explosive gases or vapors in the combustion chamber. This is accomplished as follows.

Pivoted at 163 to the abutment 100 is an electrically grounded bell crank or lever 164. Secured to this crank at 165 is an arm 166 carrying grounded contact 167. The arm 168 of the crank also carries a grounded contact 169 and a button 170 of insulating material. The contact 167 is threaded into the arm 166 and secured in adjusted position therein by means of a lock nut 171. Likewise the button 170 and the contact 169 are threaded into the arm 168 and secured in adjusted position by means of lock nuts 172 and 173, respectively. The extremity of the arm 174 of the bell crank cooperates with the collar 96 on the end of the rod 95 and is thus caused to move therewith.

Cooperating with the contact 167 is a contact 175 carried by a bimetallic element 176, forming a switch of the general type shown in perspective in Fig. 5. Surrounding the bimetallic element 176 is a resistance coil 177 (see Fig. 22) one end of which is connected to contact 175 and the other end of which is connected to one terminal of the primary coil 178 of a transformer 179. The secondary of the transformer is connected to the spark points 157 and 158. The bimetallic element 176 is rigidly secured at one end to a post 180 (see Figs. 1, 5 and 7). Engaging the free end 183 of the element 176 is a frame 184 of resilient wire. The opposite end of the frame 184 is adjustably secured to a post 185 by means of screw 186 passing through post 185 and engaging nut 187 secured to spring frame 184. The screw 186 is so adjusted that the spring frame compresses the bimetallic element longitudinally to the extent that the element is stressed and slightly bowed, as shown in Figs. 1, 5 and 7, it being understood that the portion of the bimetallic element having the highest coefficient of expansion is on the concave side of the element as shown in Figs. 1 and 7.

The parts are so adjusted that contacts 167 and 175 engage before spring 103 snaps to the position 103' which starts the fuel flowing from the nozzle. The engagement of these contacts closes the circuit through the primary of the transformer and an arc or stream of sparks is already passing between the contacts 157 and 158 before the fuel is projected from the nozzle.

It will be observed from Fig. 22 that this circuit through the primary of the transformer includes the electrical resistance heating coil surrounding bimetallic element 176 which begins to heat the element and cause stresses therein tending to reverse its curvature. After a predetermined interval of spark operation the stresses developed in the bimetallic element 176 become sufficient to cause it to reverse its curvature and snap from its position against stop 188 (see Figs. 1 and 7) to a position against stop 189, thus breaking the ignition circuit.

Referring first to Figs. 1, 7 and 22 and later to Figs. 1, 2 and 3, it will be apparent that as contact 167 moves towards contact 175 to close the ignition circuit, contact 169 will move toward contact 190 which is carried by a flat spring element 191 having in its normally unrestrained condition the position shown in Fig. 3, and which is secured to a post 192. The post 192 is electrically connected through a conductor 193 molded in the base B to one terminal 194 of an electrical resistance heating element 195 surrounding a bimetallic element 196 forming a portion of switch 159. The switch 159, generally speaking,

is similar to the switch shown in Fig. 5. That is to say, the bimetallic element 196 is rigidly secured at one end to a post 197. The free end of the element 196 is engaged by the spring frame 184', the rear end of which is secured to post 185' by means of adjusting screw 186', which passes through the post 185' and engages nut 187' on the frame. The other end of the electrical resistance heating element 195 is connected to contact 198 which cooperates with a fixed contact 199 electrically connected to contact 141.

Referring particularly to Fig. 2, 200 represents the fire pot or combustion chamber into which the flame from the nozzle is projected. Stretched across this chamber and in a position where it will be heated by the combustion of the fuel is a wire 201 one end of which is anchored to a suitable abutment 202 and the other end of which is adjustably anchored, as at 203, to an arm 204 pivoted at 205 to an abutment 206 on the outside of the combustion chamber opposite the abutment 202. The arm 204 is normally urged to the left, as viewed in Fig. 2, by a tension spring 207. The lower end of the arm 204 is bent inwardly at right angles toward the spring element 191 which carries contact 190, and is bifurcated as shown at 208. Pivotedly mounted at 209 in the bifurcation is a cam or wedge 210 which is urged toward and into contact with the flat spring 191 by a spring 211. The face 212 of the cam 210 which contacts the flat spring 191 is curved to a fairly large radius and is designed to function as a "space filler" between the spring 191 and the inturned end of the arm 204.

When the burner is ignited, the wire 201 will be heated and expand. This expansion will permit the spring 207 to retract the arm 204 and thus permit the spring 191 to move contact 190 away from the approaching contact 169. As long as the fuel continues to burn wire 201 remains expanded and contact 169 never reaches contact 190. On the other hand, should the burner become extinguished for any reason or should it fail to ignite from the spark, it will be evident that in the first contingency wire 201 will immediately cool and in the second contingency it will never have been heated.

Assuming that the fuel has failed to ignite, contact 190 will remain in the position shown in Fig. 1 and the parts are so adjusted that within a few seconds after the ignition circuit is closed through contacts 167 and 175 the contact 169 will engage contact 190 thus closing a circuit through the electrical resistance heating element 195 on the switch 159. The heat developed by this element surrounding the bimetallic element 196 will create stress in element 196 tending to cause it to change its direction of curvature. When the stress has reached a certain magnitude, the bimetallic element 196 will instantly change its curvature and switch 159 will snap over against the stop 213 and separate contacts 198 and 199 thus breaking the circuit through the steam generator.

In the event the burner has ignited but has been extinguished, wire 201 will immediately contract and cam 210 will immediately force spring element 191 to the right, as shown in Fig. 3, thus bringing contact 190 against contact 169 and accomplishing the result just hereinbefore described. After the spring element 191 has been forced into contact with the rigid piece 214, further contraction of the wire 201 will merely cause the cam 210 to revolve in contact with the surface of the spring element 191 to the position 75

shown in the dotted lines 210' in Fig. 3. Thus the cam 210 may be said practically to synchronize the movement of contact 190 towards contact 169 with the contraction of the wire 201.

5 When the steam generator is shut off, of course, the steam pressure falls. The bellows 85 then expands under the influence of the spring 83 and retracts rod 95 to the right, as viewed in Fig. 7. This movement of the rod 95 also moves the arm 168 of the bell crank 164, and insulating button 170 is brought into contact with the U-shaped metal strip 215 associated with the spring frame 184. This will gradually force the spring frame from its position against the stop post 188 over to the position against the stop post 186 as shown in Figs. 1 and 7. Thus the ignition switch is reset automatically for operation.

If for any reason the steam pressure in the generator should become excessive due to a plugged nozzle or to any other cause, the circuit through the generator will be broken as follows:

As the steam pressure increases, rod 95 is pushed further and further to the left as viewed in Fig. 7 and the nut 119 on the end of the plunger 165 may be adjusted to contact with the arm 118 of the lever 117 at any desired steam pressure. When the adjusting nut 119 contacts the arm 118 it will push the arm to the left as viewed in Fig. 7. This will move the arm 120 of the lever 117 to the right against the compression of spring 121. As the arm 120 moves to the right, plunger 135 will be urged to the right by the compression of spring 136 and this will force the spring carrying contact 140 from the position 132' to the position 132, as shown in Fig. 13, thus breaking the circuit through the generator. If the ignition spark should fail, of course the fuel will not ignite, contact 190 will not move away from approaching contact 169, and the circuit through the steam generator will be broken by the opening of switch 159 a short time after contact 169 engages contact 190.

In Fig. 6 I have shown a modified form of manually-closed-automatically-opened switch which 45 may be substituted for switch 159. Here, the bimetallic element 300 is secured in slightly bowed position between a fixed abutment 301 and a yielding abutment 302 comprising the plunger 303, compression spring 304 and adjusting screw 305. An electrical resistance heating element 306 surrounds the bimetallic element and functions exactly as the element 195 in switch 159. A contact 307 similar to contact 198 is carried by element 300 and cooperates with a fixed contact 308. It is understood that the metal having the highest coefficient of expansion is on the concave side of the bimetallic element when cool and as shown in Fig. 6. When the bimetallic element is heated 55 it snaps to the position 300' and is manually reset 60 by button 309.

From the foregoing it will be apparent that every possible contingency in the operation of my burner has been provided for. For example, if the water pressure in the supply main fails or 65 falls to such an extent that additional water cannot be supplied to the steam generator, contacts 140 and 141 will automatically separate thus opening the circuit through the steam generator. Should the steam pressure in the generator be- 70 come excessive for any reason, contacts 140 and 141 will be automatically separated and break the circuit through the generator. If the fuel fails to ignite, the circuit through the generator will be automatically broken after a short interval. If the burner is operating and becomes extinguished

for any reason, the circuit will also be automatically broken through the steam generator.

Whenever the switch 159 is opened it must be closed by hand. This I consider a rather important feature because it provides an opportunity 5 for the dissipation of any explosive mixture in the combustion chamber in the time which must elapse before the device can be put into operation, thus eliminating all danger of explosion.

The electrical connections for my burner will 10 be apparent from a consideration of the wiring diagram shown in Fig. 22. In setting up the device, the primary 178 of the transformer 179 is connected to the binding posts P and P' shown in Figs. 1 and 7, and the terminal 49 for electrode 15 46 is connected to the binding post K on switch 159. One of the main lines 160 is illustrated as grounded according to the usual practice in A. C. installations, it being understood, however, that in practice a grounded conductor forms the return leg of the circuit. The live leg of the supply 20 is connected to binding post P.

While my device will operate either on direct or alternating current, it is preferable to employ alternating current wherever possible in view 25 of the fact that electrical contacts may be made and broken with less erosion to the contacting parts.

While I have described my invention in its preferred embodiment, it is to be understood that 30 the words which I have used are words of description rather than of limitation and that changes within the purview of the appended claims may be made without departing from the true scope and spirit of my invention in its broader aspects. 35

What I claim is:

1. In a device of the character described including a liquid fuel burner, means for supplying liquid fuel thereto and a steam generator for supplying fuel atomizing steam for said burner, the combination with electrical means for igniting the fuel at the burner, a switch, and an electric circuit including said igniting means and switch, of means operable in response to steam pressure in said generator for closing said switch whereby 45 said igniting means is energized.

2. In a device of the character described including a liquid fuel burner, means for supplying liquid fuel thereto and a steam generator for supplying fuel atomizing steam to said burner, the combination with electrical means for igniting the fuel at the burner, a switch, and an electric circuit including said igniting means and said switch, of means operable in response to steam pressure in said generator for closing said switch whereby 55 said igniting means is energized and a thermostatic switch for opening said circuit after a predetermined time interval.

3. In a device of the character described including a liquid fuel burner, means for supplying liquid fuel thereto and a steam generator for supplying fuel atomizing steam to said burner, the combination with electrical means for igniting the fuel at the burner, a switch, and an electric circuit including said igniting means and 60 switch, of means operable in response to steam pressure in said generator for closing said switch whereby said igniting means is energized and a thermostatic switch actuated by heat generated by the current in said circuit for opening said circuit after a predetermined time interval. 70

4. In a device of the character described including a liquid fuel burner, means for supplying liquid fuel thereto and a steam generator for supplying fuel atomizing steam to said burner, an 75

- electric circuit including electrical means for heating the water in said generator, electrical means for igniting the fuel at the burner, a first switch and a second switch, means operable in response to steam pressure of a predetermined magnitude in said generator for closing said first and second switches in predeterminedly timed order, a first thermostatic switch having a heating coil controlled by said first switch and operating coil controlled by said first switch and operating able to open the circuit to said igniting means after a predetermined time interval of operation thereof, and a second thermostatic switch having a heating coil controlled by said second switch and operable to open the circuit to said heating means upon a failure of the fuel to ignite.
5. In a device of the character described including a liquid fuel burner, means for supplying liquid fuel thereto and a steam generator for supplying fuel atomizing steam to said burner, electrical means for heating the water in said generator, a first electric circuit including said heating means and a switch adapted normally to close said circuit, a second electric circuit including means for effecting an actuating movement of 10 said normally closed switch to open the same and break the circuit through the heating means, a normally open switch in said second circuit comprising two movable contacts, means operable by the steam pressure in said generator for moving one of said contacts toward the other with increasing steam pressure and in the opposite direction with a decreasing steam pressure, and means for automatically moving the second contact away from the first contact upon ignition of the burner and toward and into contact with said first contact upon an extinguishing of the flame to close 15 said second circuit and thereby break the circuit through said heating means.
6. In a device of the character described including a liquid fuel burner, means for supplying liquid fuel thereto and a steam generator for supplying fuel atomizing steam to said burner, electrical heating means for heating the water in said generator, an electric circuit including said heating means, an element exposed to heat from said burner and adapted to expand when heated and contract when cooled, and means actuated by the contraction of said element for breaking said circuit.
7. In a device of the character described including a liquid fuel burner, means for supplying liquid fuel thereto and a steam generator for supplying fuel atomizing steam to said burner, electrical means for heating the water in said generator, an electric circuit including said means, a switch for opening and closing said circuit, a first movable element for effecting a circuit opening movement of said switch, a second element exposed to heat from said burner and adapted to expand when heated and contract when cooled, and means operatively associated with said elements permitting an expansion movement of the second element independent of movement of the first element but effecting a simultaneous movement of both elements upon a contraction of the second element.
8. In a device of the character described including a liquid fuel burner, means for supplying liquid fuel thereto and a steam generator for supplying fuel atomizing steam to said burner, electrical fuel-igniting means, electrical means for heating the water in said generator, an electrical circuit including said heating means and ignition means, a first switch normally closing the circuit through the heating means and comprising a bi-
- metallic arm and a heating element, a normally open, second switch for connecting said heating element in circuit whereby to open said first switch, and means responsive to steam pressure within said generator and heat responsive means operable in response to heat generated by said burner for closing said second switch whereby in the event of failure of fuel ignition said first switch is opened.
9. In a device of the character described including a liquid fuel burner, means for supplying liquid fuel thereto and a steam generator for supplying fuel atomizing steam to said burner, electrical ignition means for the fuel, an electric circuit including said ignition means, means for heating the water in said generator, electrical timing means operable after a predetermined period of operation of the ignition means for terminating the operation of said ignition means, heat responsive means operable in response to heat generated by said burner, means responsive to steam pressure within said generator and a switch controlled by said two last mentioned means for controlling the operation of said water heating means.
10. In a device of the character described including a liquid fuel burner, means for supplying liquid fuel thereto and a steam generator for supplying fuel atomizing steam to said burner, means for supplying water to said generator, an electric circuit including electrical means for heating the water in said generator, a first switch for controlling the operation of said heating means, electric fuel-igniting means, a second switch for controlling the operation thereof, means disposed in said water supply means and responsive to water pressure therein adapted normally to maintain said first switch closed but operable upon a predetermined drop in water pressure to open the same, and means responsive to steam pressure in said generator for closing said second switch and operable in response to a predetermined, relatively high steam pressure to open said first switch.
11. In a control system for liquid fuel burners including means for supplying liquid fuel thereto and a steam generator for supplying fuel atomizing steam to said burner, an electric circuit including a thermostat, electric ignition means, a switch including means operable in response to steam pressure within said generator for closing the circuit through said ignition means, electrical timing means in circuit with said ignition means for opening said switch after a predetermined time interval of operation of said ignition means, electrical water heating means for said generator, a normally closed switch in series with said water heating means, electrical timing means adapted to open said last mentioned switch and heat responsive means operable in response to heat generated by said burner adapted to connect said last mentioned timing means in circuit when combustion fails to take place in the burner; said pressure responsive means being operable to close said first mentioned switch whereby said ignition means is energized and thereafter to connect said last mentioned electrical timing means in circuit whereby the circuit through said last mentioned switch is opened; and said heat responsive means being disposed within range of the heat generated by said burner to prevent closing of said last mentioned switch by said pressure responsive means while combustion occurs.
12. In a device of the character described including a liquid fuel burner, means for supplying

liquid fuel thereto and a steam generator for supplying fuel atomizing steam to said burner, electrical means for heating the water in said generator, means for igniting said fuel at the burner, an electric circuit including said igniting means and a switch, means operable in response to steam pressure in said generator for closing said switch, said switch including a thermostatic element operable by heat generated by the current in said circuit for opening the same after a predetermined time interval, and said circuit including in

series the water heating means and a thermostatic switch having a heating coil, heat responsive means disposed to be affected by heat from the burner, and a switch controlled by said steam pressure-responsive means and by said heat responsive means for closing a circuit through said heating coil whereby said circuit is opened by said thermostatic switch in the event of failure of fuel ignition. 5

WILLIAM C. MASON. 10
